UNITED STATES PATENT OFFICE.

WILLIAM J. MCGALL, OF ORANGE VALLEY, NEW JERSEY.

HAT-FINISHING PROCESS AND APPARATUS.

SPECIFICATION forming part of Letters Patent No. 242,347, dated May 31, 1881.

Application filed January 20, 1881. (No model.)

To all whom it may concern:

Be it known that I, WILLIAM J. MCGALL, a citizen of the United States, residing at Orange Valley, in the county of Essex, State of New Jersey, have invented a new and useful Improvement in Hat-Finishing Processes and Apparatus, of which the following is a description.

My invention relates to certain improvements in finishing hats by a bath of heated sand or equivalent material; and it consists, first, in the employment of pressure upon the surface of the heated sand when poured into a box containing the hat upon a block or flange.

My apparatus consists, secondly, in a sand-hopper provided with steam pipes or chambers to keep the sand in a heated condition, and having a gate or outlet at the bottom for discharging the sand upon the hat at pleasure; thirdly, in a box for holding the hat upon a flange, and keeping the hot sand in contact with it; and, fourthly, in a press for forcing the sand into the closest contact with the hat while drying out its moisture.

In the drawings annexed, Figure 1 is a sectional elevation of a work-bench provided with all my appliances for hat-finishing by hot sand. Fig. 2 is a central vertical section of the sand-box and hat-flange upon a larger scale. Fig. 3 is a vertical cross-section of a sand-hopper heated by a coil. Fig. 4 is a similar view of a hopper constructed with steam-jacket. Fig. 5 is a plan of the apparatus shown in Fig. 1, four presses being shown and four sand-boxes, two of the latter being represented under the screws of the presses, and two of them receiving sand from the hopper-spouts, and Fig. 6 is a front view of a section of the hopper with one spout and gate thereon.

A is the sand-heater, consisting of a trough or hopper, supported in any convenient manner over the work-table B, and provided with outlets *a*, which may be formed in the front at the lower edge, and provided with spouts *a'*, as shown in Fig. 1, or formed directly in the bottom, as in Fig. 3, gates *b* being provided to open and close them at pleasure. By this duplicate arrangement of the outlets a number of hats may be operated upon consecutively, and one workman attend several presses and sand-boxes. I have therefore shown four presses

and sand-boxes in the plan in Fig. 5, a press, C, being arranged over the table in front of each outlet, and a sand-box, D, and hat-flange *d* being provided for each press. The sand-box is formed with bottom and sides and open top, and a hat-flange of any desired shape may be secured in the bottom by screws, as shown in Fig. 2. The hat-block *c* is preferably secured to the flange by springs *c'*, a pair of such springs being arranged to project upward from the middle of the flange, and to gripe the block by expanding inside a hole formed in the under side of it. By this construction the hat may be readily removed from the box with the block, and the latter replaced upon the flange when another hat has been applied to it.

The hat may be secured to the block by a cord at the band or covered with a cloth in the ordinary manner. In any case it is wet or sponged before applying the sand, and the latter is then drawn from the hopper upon it by opening the gate *b*. When the hat is covered with hot sand the latter has a plate of wood or metal, *f*, laid over it, and the box is placed under the screw in press C, and pressure applied to the plate to force the sand into close contact with the hat.

The presses are preferably arranged along the front edge of the work-table and the sand-hopper along the rear, and the hats are therefore easily transferred from the outlet *a* to the press by a slight forward movement.

When the operator has placed one hat in a press he can prepare another and submit it to the same process, and thus operate upon a number consecutively while the first is shaping under the influence of the heat and pressure of the sand. When the operator removes the hat and sand-box from the press he can restore the sand to the hopper by dumping it therein from the sand-box, the hat being retained in its place by the springs upon the hat-flange keeping the block in place.

If the hopper be constructed upon a large scale it may be too high to permit such an operation, and I have therefore devised the following means of returning the sand to the hopper to be reheated:

A trough, E, is formed under the table, having sides inclining toward both front and back, and the front edge conveniently arranged for

the operator to empty the sand-boxes therein. When thus emptied the sand flows down the inclined side toward the back of the table, where it may easily be shoveled out by an attendant and replaced in the hopper.

5 If preferred, an elevator-belt carrying buckets may be placed behind the table and operated by hand or steam power to raise the sand from the trough E to the sand-hopper.

10 The brim may be curled or shaped entirely by hand after the crown is finished, or a curled flange may be placed in the sand-box, as shown in Fig. 2.

15 The sand in the hopper may be heated in any desired manner, as by long pipes i, (shown in Figs. 1 and 5,) by a coil or coils, i', as seen in Fig. 3, or by a steam-jacket, i'', surrounding the hopper, as shown in Fig. 4.

20 To keep the sand-box and its flange d hot, the work-table B may be provided with a superficial steam-plate, or may itself be made of iron and hollow, as at e e e e, to receive steam inside.

25 I am aware that a bath of heated sand poured upon the hat in a conical box mounted upon trunnions has been used heretofore, and I do not therefore claim the use of loose sand, broadly; but my invention consists in the combination of pressure with the weight of the sand 30 when poured loosely upon the hat, and in the arrangements of mechanism described for manipulating the sand and the hat with greater facility than has heretofore been possible. I have therefore devised the open sand-trough 35 provided with outlets and gates, and the table provided with steam inside to keep the hat-flanges hot under the presses, as well as the combination of the presses and the hopper with a work-table adapted to sustain a number of the 40 boxes D at once, and thereby enable the operator to act upon several hats in rapid succession.

I am aware that sand and fluid substances have been confined in bags and used for press-

ing hats; but the operation of such devices is 45 much more imperfect and troublesome than the use of the loose sand in the manner described herein; and

I therefore claim my invention in the following manner:

50 1. In combination with the bath of heated sand poured loosely over the hat in the box upon a table in the manner described, the application of pressure to the surface of the sand, substantially as and for the purpose set forth. 55

2. In combination with the box D, provided with the holding-springs c', the hat-block e, provided with an opening upon its under side to engage with the springs, and the flange d removably fastened to the bottom of the box, 60 so that it can be changed at pleasure, substantially as and for the purpose set forth.

3. In combination with the table supporting the sand-box D, the press C, operating to press upon the sand in the box, in the manner herein 65 set forth.

4. In combination with the table supporting the sand-box D, the open trough or sand-hopper A, means for heating the sand, as herein described, and for discharging it into the sand-box, as by outlets a and gates b, substantially 70 as and for the purpose described.

5. The combination, with the table for supporting the sand-boxes D, of the open sand-hopper A, provided with gates b and outlets a, 75 and the presses C, arranged and operating substantially as and for the purpose set forth.

6. The combination of the table B, carrying the boxes D, with the sand-hopper A, presses C, and trough E for receiving the sand from 80 the boxes D, substantially as and for the purpose set forth.

In testimony that I claim the foregoing I have hereto set my hand.

WILLIAM J. McGALL.
